CLAMP FOR PAPER-CUTTING MACHINES

William C. Rupp, Parma, Ohio, assignor to The Chandler & Price Company, Cleveland, Ohio, a corporation of Ohio

Application November 16, 1948, Serial No. 60,341

7 Claims. (Cl. 164—51)

1

This invention relates, as indicated, to a clamp for a paper cutting machine and, more particularly, to power-operated hold-down or binder clamp means of novel construction.

Paper cutting machines of the type with which this invention is concerned may be of the general form illustrated and described in Tyler et al. Patent No. 1,967,600 and Reichert et al. Patent No. 2,305,735, for example. In such machines a fly-wheel driven by an electric motor may be connected through clutch means with a crank adapted to reciprocate the knife to cut a stack of sheets. It is necessary to clamp such stack tightly until the cut has been completed and the knife withdrawn, and a hand-wheel operated screw clamp is commonly provided for such purpose. It is also known to operate such clamp through mechanism including the same clutch adapted to reciprocate the knife so that both clamp and knife will be power operated in synchronism.

A primary object of my invention is to provide a power-operated binder clamp which will be much more rapid and efficient in operation than the common hand clamp means.

A further object is to provide for automatic actuation of such clamp in timed relation to actuation of the knife, while at the same time permitting power operation of either the clamp or knife individually, when desired.

Another object is to provide a power-operated paper cutting machine of less costly construction than any known in the prior art but which will have the novel advantages indicated above.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a front elevational view of a paper cutting machine embodying my invention, partly broken away to show certain elements of internal construction;

Fig. 2 is a vertical sectional view taken along the line 2—2 on Fig. 1;

Fig. 3 is a wiring diagram showing the arrangement of the electric control means; and

Fig. 4 is a rear elevational view of the drive

2

mechanism of the machine showing one well-known form of clutch and drive means for the cutter.

Referring now more particularly to said drawing and especially Fig. 1 thereof, there is there illustrated a paper cutting machine which embodies the novel features of my invention. As is conventional in such machines, a wide horizontal table 1 is mounted on a heavy cast frame 2 adapted rigidly to support the same. An adjustable back gauge 3 which may be of the type disclosed in Reichart Patent No. 2,203,547 is provided together with a traveling steel tape 4 indicating the position of such gauge. A knife 5 is secured by means of screws 6 to a knife bar 7 which is mounted for vertical reciprocation in upper frame 8. A wooden knife stick 9 is inset in the upper surface of table 1 to avoid possible damage to the knife.

The knife bar 7 and knife 5 are adapted thus to be reciprocated in conventional manner by means of a connecting rod 10, crank 11 and crankshaft 12 driven through a clutch 45 from a flywheel 42 driven by an electric motor 40. Such clutch is adapted to be operated through a clutch lever 13 which may be of a dual motion safety type such as that requiring the same to be first moved to the right and then to the left to cause engagement of such clutch to reciprocate the knife bar. When one cycle of operation has been completed, the clutch will be automatically kicked out and the knife left in elevated position.

Back gauge 3 may be shifted back and forth as desired by means of hand-wheel 14 and locked in adjusted position by locking lever 15. All of the above-described mechanism is conventional in various paper cutting machines now on the market.

Referring now more particularly to Fig. 2 of the drawing, I provide a vertically reciprocable binder clamp shoe 16 carried by a screw 17 threadably engaging nut 18 in such shoe which is located directly behind knife 5. As shown in Figs. 1 and 2, this shoe normally projects slightly downwardly below the edge of knife 5 when shoe and knife are in elevated position. Screw 17 is driven by a reversible electric torque motor 19 through a speed reducer 20 carried by upper frame 8. Such motor is of a type which may be temporarily stalled without damage thereto.

Referring now to Fig. 3 of the drawing, two parallel electric circuits are provided including relays 21 and 22 respectively operative to open and close corresponding contacts 21' and 22' for such motor 19 to reverse the same. Operation of

relay 21 will cause screw 17 to be driven in a direction to elevate binder clamp 16 and operation of relay 22 is effective to cause rotation of screw 17 to lower such clamp.

The crank 11 which operates to reciprocate connecting rod 10 and thereby the knife 5, is driven by an electric motor 40 through V-belts 41, flywheel 42, drive shaft 43, and worm and gear unit 44. The flywheel unit includes a clutch 45 adapted to be actuated through shifting of cone 46 releasably to engage flywheel 42 with shaft 43. Shifter cone 47 is likewise operative to apply brake 48 to stop rotation of shaft 43 simultaneously with disengagement of clutch 45. Such cones 46 and 47 are adapted thus to be reciprocated by means of clutch lever 13 and yoke 49 pivotally mounted at 50. As previously indicated, conventional mechanism will ordinarily also be provided to ensure single-cycle operation, the clutch being disengaged and the brake applied automatically after the knife has been reciprocated to make the cut and returned to elevated position. The particular drive means thus employed to operate the knife forms no part of the present invention.

Now considering Figs. 1 and 3 together, the remainder of the mechanism will be described in conjunction with an explanation of the operation thereof. A selector switch 23 may be turned to select either "Hand" or "Automatic" operation. When turned to "Hand," switches 23A and 23B will be open. The binder clamp 16 may now be raised or lowered independently of knife bar 7 by pressing switch buttons 24 and 25 respectively. When switch 25 is thus manually held closed, current will pass through normally closed switch 26 and relay 22 causing motor 19 to be operated to move clamp 16 downwardly. Upon pressing switch 24, current will now flow through normally closed switch 27 and relay 21 to cause motor 19 to operate in the reverse direction to elevate such clamp. When the clamp reaches fully elevated position as shown in Fig. 2, it will engage such limit switch 27 to open the same, thereby stopping the motor (since switches 23B and 25 are both open).

Now turning selector 23 to "Automatic," switches 23A and 23B are both closed. After the stack of sheets 28 has been properly arranged on table 1 against back gauge 3, the operator then moves clutch lever 13 first to the right and then to the left to cause engagement of clutch and rotation of crankshaft 12. The preliminary movement of lever 13 to the right operated limit switch 29 completing the circuit through switch 23B, switch 26, and relay 22 to initiate downward movement of the binder clamp 16. It will be seen, therefore, that such clamp starts its downward movement before the clutch is engaged to rotate crankshaft 12 and crank 11 to reciprocate the knife. This means that the stack of sheets 28 will always be firmly clamped by the binder clamp shoe before the knife engages the same. As above explained, the motor 19 merely stalls for the brief period (about one second) which is required for the knife to make the cut and return. A cam 30 is mounted on shaft 12 to turn therewith and is positioned to engage and operate switch 26 just prior to completion of upward reciprocation of the knife after making the cut. Engagement of cam 30 with normally closed switch 26 causes the latter to open and simultaneously closes normally open contacts 26A. Opening of switch 26 de-energizes relay 22 as well as holding circuit 29, permitting switch 29 to reopen. Closing of

contacts 26A completes the circuit through switch 23A, normally closed switch 27 and relay 21 with the result that motor 19 is now reversed to elevate the binder clamp 16. Such binder clamp is therefore not raised from the stack 28 until after the knife 5 is clear thereof. As the binder clamp nears completion of its upward movement, it engages limit switch 27 and opens the same, thereby breaking the circuit and stopping motor 19. Such interruption of the circuit likewise breaks holding circuit 26A', permitting switch 26A to reopen and switch 26 to close. Since, as above described, the knife operating clutch is automatically kicked out after completion of one cycle and the clutch handle 13 automatically returned to initial position, the entire mechanism is now set up and ready for another operating cycle.

Motor 19 may be provided with a manual control 32 of well-known type of regulating the clamping pressure by means of a variable resistance in the motor circuit. Or an adjustable friction clutch may be provided, if desired.

It will be seen from the foregoing that I have provided an automatic paper cutting machine which is exceedingly flexible in operation, permitting the knife and clamp to be reciprocated independently of each other when desired. I have found that my new machine may be operated at a rate of forty cuts per minute which is considerably faster than the operator is able to load the same.

The electrical interconnection of the controls ensures that positive clamping pressure will be maintained on the stack from a moment before the knife begins the cut until after the knife is withdrawn. The entire device is substantially foolproof and the work produced is of uniformly high quality even when employing relatively unskilled operators.

Other modes of applying the principle of the invention may be employed, change being made as regards the details described, provided the features stated in any of the following claims or the equivalent of such be employed.

I therefore particularly point out and distinctly claim as my invention:

1. In a power-operated paper cutting machine having a knife, crank means adapted to reciprocate such knife, and a clutch-operating lever operative to connect such crank with drive means therefor; a reciprocable clamp adapted to clamp the work during such cutting operation, screw means threadedly engaging said clamp to thus reciprocate the same, a reversible electric torque motor mounted to drive said screw means, a switch adapted to be actuated by such clutch-operating lever when the latter is shifted to initiate reciprocation of such knife, actuation of such switch completing the circuit of said motor to drive said screw means to advance said clamp, a cam rotatable with such knife-reciprocating crank means, switch means positioned to be actuated by said cam after rotation of such crank to reciprocate such knife to make the cut and return such knife from the cut, actuation of said last-named switch means interrupting such motor circuit and completing the motor circuit effective to reverse the direction of rotation of said screw means and thereby retract said clamp, and a limit switch engageable by said clamp in retracted position to stop said motor.

2. In a paper cutting machine having a table adapted to support a stack of sheets thereon, a vertically reciprocable clamp adapted to clamp

such stack on such table, and a knife operative to cut such stack thus clamped; means operative to raise and lower such clamp comprising a vertically disposed screw mounted against axial movement and threadedly engaging such clamp, a reversible electric torque motor mounted to drive said screw to raise and lower such clamp, switch means automatically operable to energize said motor to lower such clamp in advance of downward cutting movement of such knife, switch means automatically operative after completion of such cut and withdrawal of such knife to reverse said motor to raise such clamp, and a limit switch engageable by such clamp in elevated position operative to stop said motor.

3. In a paper cutting machine having a table adapted to support a stack of sheets thereon, a vertically reciprocable clamp adapted to clamp such stack on such table, and a knife operative to cut such stack thus clamped; means operative to raise and lower such clamp comprising a reversible electric torque motor, means driven by said motor engaging such clamp operative to raise and lower the latter as determined by the direction of operation of said motor, manual control means operative to initiate reciprocation of such knife, switch means automatically operable by preliminary movement of said knife control means to energize said motor to lower such clamp in advance of such knife, switch means automatically operative after completion of such cut and withdrawal of such knife to reverse said motor to raise such clamp, and switch means operative to stop said motor upon return of such clamp to elevated position.

4. In a paper cutting machine having a table adapted to support a stack of sheets thereon, a vertically reciprocable clamp adapted to clamp such stack on such table, and a knife operative to cut such stack thus clamped; means operative to raise and lower such clamp comprising a reversible electric torque motor operative when driven in one direction to lower such clamp and when driven in the other direction to raise the same, control means operative to initiate reciprocation of such knife, means responsive to operation of said control means adapted to energize said motor to lower such clamp in advance of such knife, means operative after return of such knife from the cut to reverse said motor to elevate such clamp, and means adapted automatically to stop said motor upon return of such clamp to elevated position.

5. In a paper cutting machine having a clamp reciprocable into and out of clamping position, a knife operative to cut such stack thus clamped; means operative to reciprocate such clamp comprising a reversible electric torque motor, drive means connected with said motor and clamp adapted to be driven by said motor and operative when driven in one direction to move such

clamp into clamping position and when driven in the other direction to move such clamp into unclamped position, control means operative to actuate said motor to drive such clamp to clamp the work and to reverse said motor to drive such clamp to unclamp the work, and means automatically operative to time such actuation of said motor in relation to movement of such knife to clamp the work prior to engagement of such knife with the work and to unclamp the work only after such knife has returned from the cut.

5. In a paper cutting machine having a table adapted to support a stack of sheets thereon, a vertically reciprocable clamp adapted to clamp such stack on such table, and a knife operative to cut such stack thus clamped; means operative to raise and lower such clamp comprising reversible clamp drive means, a stallable electric torque motor adapted to operate said drive means, control means adapted to energize said motor to lower such clamp, said motor being adapted to stall without harm thereto during a short clamping period, whereby such stack may be actively clamped during performance of the cutting operation, control means automatically operative to reverse said motor to raise such clamp after completion of such cutting operation, and control means automatically operative to de-energize said motor when such clamp has been fully raised thereby.

7. In a paper cutting machine having a table adapted to support a stack of sheets thereon, a vertically reciprocable clamp adapted to clamp such stack on such table, a knife mounted to cut such stack thus clamped, and separate drive means for such clamp and knife; drive means for such clamp comprising a reversible, stallable electric torque motor, screw means engaging such clamp and adapted to be driven by said motor to raise and lower such clamp, control means adapted to energize said motor to lower such clamp, said motor being adapted to stall without harm thereto during a short clamping period whereby such stack may be firmly and actively clamped during performance of the cutting operation, control means actuated by such knife drive means automatically operative to reverse said motor to raise such clamp after completion of such cutting operation and withdrawal of such knife from the cut, and control means automatically operative to de-energize said motor when such clamp has been fully raised thereby.
